UNITED STATES PATENT OFFICE.

VERNON M. GREGG, OF CEDAR FALLS, IOWA.

COMBINATION DENTAL TRAY.

Application filed February 14, 1927. Serial No. 167,952.

My invention relates to improvements in combination dental trays, and the object of my improvement is to supply for a superposed pair of such trays adjustable alining 5 connecting means and a removal adjustable resilient clamping fastener for such connecting means.

This object I have accomplished by the means which are hereinafter described and 10 claimed, and which are illustrated in the accompanying drawings, in which Figs. 1 to 3 inclusive are perspective views of the two trays and of the removable fastening means therefor as disassembled, and Fig. 4 is a side 15 elevation of said trays as assembled with said fastening means. Fig. 5 is a front end elevation of said devices as shown in said Fig. 1.

It is to be understood that various modifications of said devices may be effected, 20 without thereby departing from the scope of this invention or the protection of its claims.

The numerals 1 and 6 denote dental trays 25 of a well-known type, which may be used singly in taking impressions of the upper and lower teeth and jaw parts and other parts of the oral cavity in plastic wax, previously placed in the trays. After taking 30 both sets of impressions, the trays are placed in superposition, releasably secured together after longitudinal adjustments have been effected therebetween when a "bite" has been taken in the shaped wax thereon by 35 the patient. It is important that the connecting means between the trays be such as to not only permit of longitudinal adjustments therebetween, but that also resilient 40 frictionally clamping means be used for the superposed contacting shanks of the trays which permit the shanks to be longitudinally adjusted upon each other, while being held under light compression, against accidental 45 displacements from each other until a final adjustment has been arrived at, when the 50 fastening means may be further manipulated or operated to be tightly yet releasably clamped upon the shanks to hold them and the trays rigidly until the operations thereof are completed.

The trays 1 and 6 have like forwardly 55 projecting shanks 2 and 7 respectively, fastened at their rear ends upon the abutting parts of the superposed trays. These shanks 60 have like longitudinal upwardly ridged angular crimps 3 and 8 respectively which fit

upon each other for longitudinal sliding relative adjustments thereof and said trays. The crimps are preferably positioned slightly within the side edges of the shanks, the 60 shanks being shaped from elongated flat metal plates, and to have each a flat intermediate space between the pair of crimps on each shank. The side edge parts 9 are in the same planes as said flat intermediate 65 parts of the shanks. The rear terminations of the shanks may be rounded convexly at 10.

I have supplied adjustable and resilient 70 fastening means for said shanks 2 and 7, shown in said Fig. 3 in perspective as removed from the shanks, and in Figs. 4 and 5 as operatively assembled with said shanks.

The fastening device comprises a closed 75 flat loop or ring part 11 whose top part has angular crimps 12 to fit upon the crimps 3 of the uppermost shank 2 when the loop is slidably mounted upon the contacting assembled shanks 2 and 7. The lower part 13 of said loop is offset downwardly to space its middle only from the middle part of the 80 under shank 7 so that the ends of this lower part 13 contact with the under face of the side parts 9 of the shank 7, whereby the loop 11 is closely yet slidably fitted upon the superposed shanks. The numeral 15 85 denotes a set-screw having a knurled head and whose threaded stem is seated in an interiorly threaded boss 14 depending from the loop part 13 medially. The upper end of said stem may be brought into compressive 90 engagement with the under medial part of the lower shank 7 to clamp the shanks 2 and 7 tightly together.

In order to elastically frictionally bind or 95 clamp said shanks together in cooperation with said screw 15, I have shaped the loop with the medial oppositely longitudinally projecting spring fingers 16 best disclosed in said Fig. 3 which fingers may be integral 100 with the loop or otherwise rigidly mounted thereon. When the said fastening device is assembled with the superposed shanks 2 and 7, to be used for a "bite", the screw 15 is turned to but lightly terminally engage the lower shank 7 permitting sliding of one 105 shank longitudinally upon the other while the operator is engaged in arriving at a suitable relative longitudinal adjustment of the trays. It will be seen that the spring fingers 16 contact with the upper medial face of the 110 upper shank 2 with a light resilient compression, which is nevertheless sufficient to

prevent slight and unnoticed displacements of one shank upon the other which would interfere with the accuracy of the adjustment. Then, after the proper adjustment of the shanks has been arrived at, it is only necessary for the operator to further turn the screw 15 to thus tightly fasten the shanks together releasably.

As it is requisite that the trays be not displaced from each other laterally while such adjustments are being made, the pair of crimps in each shank allow longitudinal adjustments of the shanks but prevent lateral displacements of one upon the other, the loop 11 having like crimps which prevent lateral swinging or displacements of the loop, yet also permitting longitudinal sliding of the loop upon the shanks.

The crimping of the shanks also strengthens them, and the crimping of the loop 11 keeps it in alinement with the shanks and from turning sidewise, so that a relatively narrow loop may be used giving wider scope of adjustments of the loop with its spring fingers upon the upper shank 2. It is to be further noted that as the loop fastener 11 is removable, the usual set of seven pairs of trays of an equipment, having differently sized trays, may have the same size shanks, so that but one loop fastener 11 is needed for the equipment, saving expense, and also allowing the instrument casing therefor to be smaller, lighter and less expensive.

Having described my invention, what I claim as new, and desire to secure by Letters Patent, is:

1. In combination, dental trays having superposed contacting relatively slidable shanks both having slidably fitting like mating longitudinal crimps, a clamping loop removably slidably loosely mounted on and to inclose said shanks, said loop having oppositely directed spring fingers to engage one shank, and a set-screw mounted in a part of the loop adjustably to engage the other shank oppositely to said spring fingers to releasably lock the shanks together upon final relative adjustment thereof.

2. In combination, dental trays having superposed contacting longitudinally crimped and mating shanks fitted slidably together for longitudinal relative adjustments, a flat loop removably slidably inclosing said shanks having like mating crimps fitting said other crimps, and detachable fastening means adjustably mounted on said loop to clamp the shanks together.

3. In combination, dental trays having like superposed longitudinally crimped shanks, the crimps fitting slidably together to prevent sidewise displacements of the shanks, and a longitudinally crimped loop inclosing said shanks loosely having its crimps fitting the crimps upon one of the shanks, said loop having oppositely directed spring fingers to resiliently engage one shank, and a set-screw mounted in said loop oppositely to said spring fingers to adjustably clamp the shanks together.

In testimony whereof I affix my signature.

VERNON M. GREGG.
